UNITED STATES PATENT OFFICE.

WASYL BYTZKA, OF HELMETTA, NEW JERSEY.

ASH-SIFTER.

1,357,610.

Specification of Letters Patent.

Patented Nov. 2, 1920.

Application filed April 7, 1919. Serial No. 287,946.

To all whom it may concern:

Be it known that I, WASYL BYTZKA, a citizen of Ukraine, residing at Helmetta, in the county of Middlesex and State of New Jersey, have invented certain new and useful Improvements in Ash-Sifters, of which the following is a specification.

The primary object of the invention is to provide a ready means for sifting ashes by hand in a cleanly and sanitary manner, provision being made for preventing the escape of dust and dirt during the ash sifting operation.

A further object of the invention is to provide an ash sifter that is compact in arrangement and easily and cheaply manufactured and by means of which ashes may be quickly sifted for household purposes in any desired quantity.

With these general objects in view, the invention consists of the novel combination and arrangement of parts hereinafter fully described in connection with the accompanying drawings and in which like reference characters designate corresponding parts throughout the several views,

In the drawings,

Figure 1 is a perspective view of the invention closed,

Figs. 2 and 3 are transverse sectional views taken upon lines II—II and III—III of Fig. 1,

Fig. 4 is a perspective view of the invention open ready to sift ashes,

Fig. 5 is an enlarged sectional detail view adjacent the top of the invention with the cover closed,

Fig. 6 is a front elevation of the connecting latch partially broken away, and

Fig. 7 is a perspective view of the forward end portion of the screen or sieve employed.

My invention comprises a rectangular box or casing divided into two substantially equal parts, a bottom section 10 being adapted for receiving the siftings from a sieve or screen 11 carried by the upper section 12 of the box. The sections 10 and 12 are connected by hinges 13 at one side of the box while a connecting latch 14 pivoted as at 15 to the lower section 10 is adapted to automatically engage over a pin 16 projecting from the adjacent side of the upper section 12 when the sections are closed upon each other as illustrated in Figs. 1 and 4 of the drawing. A spring 17 engages the latch 14

holding the same in contact with said pin 16 while a stop 18 upon the section 10 limits the swinging movement of said latch.

The screen 11 is removably positioned 60 through a front slot 19 in the upper section 12 and in opposite grooves 20 in the opposite sides of said upper section. In this manner, the screen 10 forms the bottom of the upper section 12 adapted to receive ashes thereon 65 when placed into the upper section upon opening the lid or cover 21 thereof.

Leaf springs 22 having their forward ends secured in grooves 23 in the upper edges 24 of the opposite sides 25 of the section 12 70 bear upon the cover 21 for automatically opening the cover when the same is released. A spring catch 26 upon the front wall 27 of the upper section 12 projects through a keeper opening 28 in the cover 21 when the 75 latter is closed and automatically engages over the side of the opening 28 for returning the cover in its closed position.

The complete operation of the device will be apparent in that the ashes are readily 80 positioned in the upper section 12 when the cover 21 is open as shown in Fig. 4 of the drawings. The cover is then closed being retained by the catch 26 and the operator grasps the device shaking the same in the 85 usual manner of a hand sifter until the ashes pass through the screen 11 into the lower section 10 while the cinders and larger particles remain in the upper section. The latch 14 is then released and the ashes 90 dumped out of the lower section 10. The cinders are readily removed from the upper section 12 by releasing the catch 26 whereupon the cover 21 automatically flies open and the cinders are readily dumped out and 95 a new supply of ashes placed into the upper section 12.

What I claim as new is:—

A sifter formed of two sections hingedly connected together, means for holding said 100 sections in closed position, the front wall of the upper section having a slot therein and grooves formed in the inner faces of the side and rear walls horizontally aligned with said slot, a sifter screen slidable through the 105 front wall slot and guided in the wall grooves for sliding movement when the sections are closed, and a cover wall hinged to the upper section.

In testimony whereof I affix my signature. 110

WASYL BYTZKA.
